COMBINATION BRUSH, SCRAPER AND SQUEE- GEE FOR CLEANING WINDSHIELDS

Anne Doster, Toronto, Ontario, Canada, assignor to
Woodbridge Moulded Products Limited, Toronto,
Ontario, Canada, a corporation of Canada

Filed June 12, 1963, Ser. No. 75,314

Term of patent 3½ years

(Cl. D9—6)

FIG. 1

FIG. 2

FIG. 3

FIG. 1 is a top plan view of a combination brush, scraper and squeegee for cleaning windshields, showing my new design;

FIG. 2 is a side elevational view thereof; and

FIG. 3 is a perspective view thereof.

The broken lines shown in FIG. 2 are for illustrative purposes only.

I claim:

The ornamental design for a combination brush, scraper and squeegee for cleaning windshields, as shown and described.
